Primary Examiner — Elizabeth Albert(74) Attorney, Agent, or Firm — Beacon Patent Intelligence;
Eugene H. Nahm(57) CLAIM

The ornamental design for a coaching board, as shown and described.

DESCRIPTION

FIG. 1 is a top, front and left side perspective view of the coaching board showing my new design;

FIG. 2 is a top plan view of FIG. 1;

FIG. 3 is a bottom plan view of FIG. 1;

FIG. 4 is a right side elevation view of FIG. 1;

FIG. 5 is a left side elevation view of FIG. 1;

FIG. 6 is a front elevation view of FIG. 1;

FIG. 7 is a rear elevation view of FIG. 1;

FIG. 8 is a top, front and left side perspective view of FIG. 1 in an open position;

FIG. 9 is a top plan view of FIG. 8;

FIG. 10 is a bottom plan view of FIG. 8;

FIG. 11 is a right side elevation view of FIG. 8;

FIG. 12 is a left side elevation view of FIG. 8;

FIG. 13 is a front elevation view of FIG. 8; and,

FIG. 14 is a rear elevation view of FIG. 8.

The broken lines in FIGS. 1, 2, 8 and 9 are included to show features on the coaching board that form no part of the claimed design.
